UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE

Application filed June 27, 1922. Serial No. 571,154.

To all whom it may concern:

Be it known that I, GEORGE A. SEIB, citizen of the United States, and resident of Ilion, in the county of Herkimer and State of New York, have invented certain new and useful Improvements in Typewriting Machines, of which the following is a specification.

My present invention relates to stop mechanisms for the type bars of writing machines, and its general object is to provide new and improved mechanisms of the character stated. More specifically my invention has for its object the provision of a new and improved anvil or type bar contact device constructed to minimize the metallic noise which has heretofore resulted from the employment of an anvil of solid metal, while at the same time practically retaining the advantages of a solid anvil construction.

To the above and other ends which will hereinafter appear, my invention consists in the features of construction, combinations 25 of devices, and arrangements of parts, hereinafter described and particularly pointed out in the claims.

In carrying out my invention I provide an anvil made of coiled wire multiple wound, that is, wound from a number of strands or wires, five for example, as in the present instance, which are led from separate spools or supply holders and wound simultaneously upon an arbor producing a hollow cable or helix. By this expedient I am able to give the wires a pitch or angle sufficient to cause the type bars always to strike them crosswise, the type bars thus being prevented from forcing their way between the wires and lodging or sticking and thus retarding or interfering with the printing operations. Preferably also the anvil is composed of two hollow cables or helices, one fitting within the other and serving as a core, as I have found by experiment that such a construction prevents collapse or distortion of the anvil when it is bent or curved into an arc and fitted into its seat in the type bar support or segment. The inner helix or core piece may be made of the same diameter or fineness of wire as the outer helix but is preferably wound oppositely so that its plies or strands cross at an angle to the outer plies or strands.

58 My invention will be described in detail

in connection with the accompanying drawings wherein.

Figure 1 is a fragmentary front elevation partly in section showing a type bar support or segment with my invention applied thereto.

Figure 2 is a vertical sectional view taken on a plane indicated by the section line 1-1 in Fig. 1 and looking in the direction of the arrows at said line, said Figure 2 being drawn to an enlarged scale and showing one of the type bars co-operatively engaged with the anvil or contact device. 65

Figure 3 is an enlarged fragmentary view of the outer helix or part of the anvil. 70

Figure 4 is an enlarged fragmentary view of the inner part or core.

Figure 5 is an enlarged fragmentary view partly in section of the anvil or contact device; and

Figure 6 is an enlarged fragmentary view of a modification.

Figures 1 and 2 of the drawings illustrate fragmentarily the type bars and type bar support of a No. 10 Remington typewriting machine to which my invention is shown applied. Said type bar support or segment 1 is arcuate in form and vertically fixed to the framing by screws 1^a below and somewhat forward of the platen 2. Said segment is formed with a series of radial kerfs or slots indicated at 3 in which the type bars 4 are arranged and whereby they are guided, each type bar being provided at its outer end with a type block 5 formed with an upper case type and a lower case type that are adapted to contact co-operatively with the front face of the platen 2. The set of type bars are pivoted on an arcuate fulcrum wire 6 which is common to all of the type bars, and is supported on the segment 1, said fulcrum wire extending transversely of the guide slots 3 and being seated in an arcuate groove cut in the rear portion of the segment. The type bars are operated by the usual trains of key actuated devices and are thereby swung upward and rearward on their fulcrums to printing position. As they approach the platen the key operated type bars co-operate with a guide opening indicated at 7 in a center guide 8 which is secured by screws 9 to the front of the segment. Arranged at either side of the center guide 8 are upstanding guide fingers or devices 10 having heads or securing portions

11 which receive headed screws 12 whereby said devices are fixed to the front face of the segment in a position to co-operate with and guide certain parts of the guiding 5 and line finding mechanism not herein shown. I have now described such of the regular parts of the machine as are necessary to a complete understanding of my invention.

10. In the Remington typewriting machine as heretofore constructed and in other typewriting machines there has been employed a type bar anvil or contact device made of solid metal, usually in the form of a projecting rib on the type bar segment. The noise resulting from the impact of the type bars on this anvil as they near the ends of their strokes is considerable and the primary purpose of my invention is to eliminate this noise as far as possible and yet to retain the advantages of the substantially constructed anvil or contact device. To this end I have replaced the solid anvil with a wire coil anvil which in the preferred 25 form comprises two parts or coils, an outer coil 13 and an inner coil or core 14. Both these coils or helices may be made of piano or spring wire of the same diameter and of sufficient elasticity to prevent permanent distortion from the blows received from the type bars. Both coils or helices are multiple wound; that is to say, instead of being wound or composed of a single wire each is preferably composed of five 35 wires or strands wound simultaneously side by side. The two coils however are wound in opposite directions. The results of such multiple winding, so far as affecting the character of the coils is concerned, will be clearly understood from an inspection of 40 Figs. 3 and 4, which show respectively portions or sections of the outer coil 13 and the inner coil 14. For the sake of clearness the five wires of coil 13 are designated in order as *a*, *b*, *c*, *d* and *e*. Beginning 45 at the right in Fig. 3 these five wires appear side by side in the coil to be succeeded by the same five in the same order; and so on. Similarly in Fig. 4 which shows the inner coil 14 the five wires of which it is 50 composed are designated in order *a'*, *b'*, *c'*, *d'* and *e'*. Beginning at the left these five wires are wound together side by side in the said order and are next succeeded by themselves in the same order; and so on. The consequence of such multiple winding 55 is that the angular disposition of each wire of the coil, or its pitch, so to speak, is sufficient to insure that the type bars will impact against the anvil always more or less crosswise of one or more of the wires of which it is composed, the type bars thus being prevented from striking between or working in between the coils of wire and 60 lodging or sticking so as to hamper or ob-

struct the operation of the type bars. In contrast to this a hollow cable or helix wound of a single wire will bring the coils almost parallel with the type bars so that they will tend to stick or lodge between 70 the coils when operated and frequently will do so as experiment has demonstrated. The coiled wire anvil when mounted in place is curved or bent into an arc concentric with the arc of the type bar pivot 6 and 75 against its own inherent tendency to remain straight, as wound; and I have found that the provision of an inner coil or core 14 overcomes difficulties in maintaining the accuracy of the anvil when bent against its inherent spring tension from a straight line into an arc, any tendency to distortion or collapse being overcome by the two-part construction. The interseating of the outer coil 13 and the inner coil 14 is clearly illustrated in Fig. 5. From this figure and from Fig. 2 it will be observed that the anvil is circular in cross section and has a hollow interior indicated at 14^a. The circular form 80 allows the wire to be turned when detached to vary the portion of the surface struck by the type bars, thus providing for wear and increasing the life of the anvil.

The anvil 13, 14 is mounted on the segment, being seated in an arcuate groove or undercut therein indicated at 15. The groove 15 is V-shaped in cross section and is cut in the front face of the segment concentric with the groove of the type bar fulcrum wire 6, and is so shaped and proportioned as to leave the front portion of the anvil projecting forward beyond the face of the segment as will be clearly understood from Fig. 2. A segmental clamp or retaining plate 16 having an angular 95 flange or contact portion 17 is detachably secured to the front face of the segment above the anvil, preferably by the screws 12, the plate 16, 17 being clamped between the front face of the segment and the under faces of the guide pieces 10, 11. The flange portion 17 of the retaining plate 100 contactively engages with the upper portion of the coiled anvil and retains it in position in its seat 15, leaving the front or contact portion of the coil projecting through and beyond an opening or slotway formed in the segment by the retaining plate 16, 17 and the undercut 15, this opening being in effect an arcuate slotway which is so narrow as to prevent the escape or displacement of the coiled anvil. In Fig. 2 the lower portion of the center guide is broken away so as to show more clearly the left-hand pair of screws 12 by which the left-hand portion of the retaining plate is 105 clamped or secured to the segment.

In some instances the inner coil or core may be dispensed with and an anvil composed of a single coil, such as or similar to 110

the outer coil 13, may be found to give satisfaction. However, as stated, I have found it preferable to employ the double coil or two-part construction as this lends itself 5 more readily to proper and accurate bending and mounting of the contact device on the type bar support.

In Fig. 6 there is illustrated a modified construction wherein the anvil is composed 10 of a single coil 18 of wire, the coil in turn being wound from a single wire instead of a plurality of wires as in the Figs. 1-5 construction. It will be noted from Fig. 6 that as a result of using a single wire in winding 15 the helix the coils comprising it extend more nearly straight across than in the first described construction. In other words, the pitch or angularity is considerably less in the Fig. 6 construction and as a result the 20 type bars will strike against the helix almost parallel with the coils so that the bars at times may stick or lodge between the coils, thus interfering with the proper operation of the type bars. For this reason I prefer to employ a multiple wound or compound helix or helices for the anvil since 25 thereby the pitch of the coils is increased to such an extent that the liability of sticking is obviated.

An anvil formed or made in the manner 30 described, and particularly the Figs. 1-5 construction, provides a contact or cushion that retains the advantages of the solid anvil while eliminating to a large extent the disagreeable metallic noises incident to the 35 use of the latter. In my construction there is a slight give or yield to the contact device or anvil when it is struck by the type bar so that the bar instead of being instantly and 40 finally arrested at the moment of contact moves slightly and of course much more slowly towards the platen until the contact device will no longer yield and finally effects the arrest of the type bar. The bar is 45 thus arrested just prior to the contact of the type with the paper on the platen, the imprint of the type being effected as the result of the whipping over of the type end of the bar due to its momentum. Following the 50 impact of the type on the paper the speed of the type bar return action is increased as the result of an impulse communicated to the bar from the slightly compressed anvil. In other words, the contact device or anvil 55 in the present invention is sufficiently elastic to give the type bar what may be termed a gradual arrest in contrast with the instant arrest of the solid anvil, thus tending to reduce the noise; and the elasticity of the present 60 contact device has the further advantage of increasing the speed of return of the type bar to its normal position. In view of the slight give or yield of the present contact device it may be found desirable to time 65 the contact of the bar with the arresting de-

vice so that this takes place slightly further from the printing face of the platen than the contact of the type bar with a solid anvil.

It will also be noted that the sound vibrations, instead of being transmitted uninterrupted through a solid metallic metal as with the prior solid anvil, are in the present instance necessarily broken up or divided thus conducing to a reduction in the amount of noise and also changing its quality by 75 lessening the sonority.

It is to be understood that the term anvil as herein employed refers to an anvil or contact device that is adapted to yield or give somewhat to the impact of the type bars in 80 contradistinction to the immovable, inflexible or solid style of anvil heretofore usually employed.

Various changes besides those specified 85 above may be made without departing from the spirit and scope of my present invention.

What I claim as new and desire to secure by Letters Patent, is:—

1. In a typewriting machine, the combination of a platen, a set of key operated type bars, and a coiled wire device arranged in the path of the type bars so as to be struck by said type bars as they near the ends of their printing strokes. 90

2. In a typewriting machine, the combination of a platen, a set of key operated type bars, and an anvil with which said type bars co-operate, said anvil being made of coiled spring wire. 95

3. In a typewriting machine, the combination of a platen, a set of key operated type bars, and an anvil with which said type bars co-operate, said anvil being made of spring wire multiple wound. 100

4. In a typewriting machine, the combination of a platen, a set of key operated type bars, and an anvil with which said type bars co-operate, said anvil comprising a core formed of a plurality of wires wound side by side. 105

5. In a typewriting machine, the combination of a platen, a set of key operated type bars, and an anvil with which said type bars co-operate, said anvil being composed of two coils of wire, one arranged inside 115 the other.

6. In a typewriting machine, the combination of a platen, a set of key operated type bars, and an anvil with which said type bars co-operate, said anvil being composed of two coils of wire, one arranged inside the other, the coils being oppositely wound. 120

7. In a typewriting machine, the combination of a platen, a set of key operated type bars, and an anvil with which said type bars co-operate, said anvil being composed of two coils of wire, one arranged inside the other, each coil being composed of a plurality of wires wound side by side. 125 130

8. In a typewriting machine, the combination of a platen, a set of key operated type bars, a support therefor, and an anvil with which said type bars co-operate, said anvil being composed of two spring coils, one arranged inside the other, each coil being composed of a plurality of wires wound side by side but in opposite directions, said anvil being bent into an arc in conformity with the arrangement of the type bars but capable of straightening itself when free.
9. In a typewriting machine, the combination of a platen, a type bar support, a set of key operated type bars thereon, and an anvil of spring wire seated in a groove in said support.
10. In a typewriting machine, the combination of a platen, a type bar support, a set of key operated type bars thereon, an

anvil circular in cross section and seated in a V-groove in said support, and a segmental retaining plate detachably secured to said support and operative to retain said anvil in place.

25

11. In a typewriting machine, the combination of a platen, a type bar support, type bars thereon, and a spring metal anvil with which said type bars co-operate, said anvil being secured to said support in an arc of a circle but through its inherent spring being adapted to straighten out when removed from said support.

Signed at Ilion, in the county of Herkimer, and State of New York, this 23rd day of June, A. D. 1922.

GEORGE A. SEIB.
